APPARATUS FOR MAKING CONDENSERS
Joseph F. Riley, Chicago, Ill., assignor, by mesne assignments, to P. R. Mallory & Co. Inc., Indianapolis, Ind., a corporation of Delaware
Original application Aug. 17, 1950, Ser. No. 180,003.
Divided and this application Mar. 22, 1954, Ser. No. 417,806

6 Claims. (Cl. 29—25.42)

This invention relates to apparatus for, and a method of making condensers.

This application is a division of my co-pending application Serial No. 180,003, filed August 17, 1950, now abandoned.

One feature of the invention is that it provides a novel and improved method of making condensers; another feature of the invention is that it provides improved apparatus for making condensers; a further feature of the invention is that it provides a method whereby a plurality of condenser body members are positioned in spaced relationship and lead wires extending from the body members are clamped to form a single portable assembly with the body members gripped between the wire ends; still another feature of the invention is that a plurality of the gripped members may be dipped simultaneously in a conductive binding agent, as molten solder, to coat the ends of the lead wires and the conductive plates of the body members gripped therebetween; yet a further feature of the invention is that the assembly may be positioned, while the solder or other binding agent is still liquid, to form a globule of solder at the junctures of the wires and conductive plates; yet a further feature of the invention is that it provides improved apparatus for positioning a plurality of condenser body members in spaced, aligned relationship, gripped between lead wires which extend from each body member, and removable means for clamping said wires to form a single readily portable assembly having the body members gripped between the lead wire ends; an additional feature of the invention is that the apparatus includes a base having a recess for positioning disc-shaped condenser body members, guide means for positioning lead wires which extend from said body members, and clamping means for clamping the lead wires to form a readily portable assembly so that a plurality of condensers can be handled as a unit.

Other features and advantages of the invention will be apparent from the following description and from the drawings, in which:

FIG. 1 is a plan view of apparatus constructed in accordance with the invention having a plurality of condenser body members positioned thereon, portions of the apparatus being broken away.

FIG. 2 is a transverse section along the line 2—2 of FIG. 1.

FIG. 3 is a plan view similar to FIG. 1, but showing a different type of condenser.

FIG. 4 is a transverse section along the line 4—4 of FIG. 3.

FIG. 5 is a plan view of the clamped condenser assembly, the center portion being broken away.

FIG. 6 is a side elevational view similar to FIG. 5.

FIG. 7 is a vertical section along the line 7—7 of FIG. 8, showing one step in the method.

FIG. 8 is an end elevational view looking from the left of FIG. 7.

FIG. 9 is a fragmentary section illustrating another step in the method; and

FIG. 10 is a perspective of a tray utilized to carry the condensers, a portion of this tray being shown in section in FIG. 9.

In television receivers, communication receivers, and

2

other electronic apparatus, particularly apparatus operating at relatively high frequencies, small "disc" condensers are very frequently used. These condensers are advantageous in that they are much smaller in physical size than paper condensers for a given capacitance. For example, a disc condenser having a diameter of $\frac{1}{4}$ inch may have a capacitance of .001 microfarad and a voltage rating of 600 v. D.C., and a condenser having a diameter of only $\frac{5}{16}$ inch may include two .001 condensers each having a voltage rating of 600 v. D.C.

Disc condensers are formed from a thin disc-shaped body member of a ceramic or other dielectric material having conductive plates on opposite sides thereof. These plates may comprise a silver coating, and in single unit condensers the coating may be circular with a diameter almost as great as the diameter of the ceramic disc. In two-unit condensers, one side of the dielectric disc may have a circular coating of conductive material to form one common plate, and the other side of the dielectric disc may have two spaced plates, each almost semi-circular in form and separated by a central uncoated strip of the dielectric disc. In manufacturing the condensers a lead wire is soldered to each conductive plate and a protective dielectric sheath is formed over the body member and the ends of the lead wires, usually by a plurality of dips in one or more coating materials.

In the past it has been the practice to handle condensers individually during manufacture, and a skilled worker could make about 3,000 condensers a day by this individual handling method. Utilizing my improved apparatus and following my novel method, it is possible for a worker to make more than 65,000 condensers a day.

Referring now more particularly to the drawings, the apparatus includes means for positioning a plurality of condenser body members, this means comprising a base having a substantially horizontal supporting surface. In the apparatus illustrated, the base is formed by a wooden block 20 having a main body member 21 of steel secured thereto, as by means of screws 22, and having a subsidiary body member 23 of steel secured thereto and extending parallel to the main body member 21 and spaced therefrom. With this construction the supporting surface is in two separated portions and includes the surface 21a of the member 21 and the surface 23a of the member 23. If desired, the base members 21 and 23 might be integral so that the supporting surface would be completely on a single part.

An elongated steel strip 25 is secured on the supporting surface portion 21a by means of bolts 26 to provide a raised portion extending longitudinally of the supporting surface. A plurality of semi-circular pockets 27 are spaced in a straight line along the periphery of the member 25, these pockets opening into the edge or periphery of the member 25 and each being adapted to receive a portion of one of the disc-shaped body members from which the condensers are to be made.

First guide means opposite each pocket may comprise posts 30 which are driven into openings in the member 23 so that they project above the supporting surface opposite the center of each pocket 27. Each post has a vertical slot as shown at 30a in FIG. 1, these slots extending all the way down to the supporting surface 23a. Second guide means opposite each pocket intermediate the first guide means 30 and the pockets may comprise similar posts driven into openings in the supporting surface 21a of the member 21. As illustrated, instead of a plurality of separate posts, an elongated strip member 32 is driven into an elongated slot in the surface 21a, the member 32 projecting above the supporting surface 21a and having a pair of outer slots 33 and a center slot 34 opposite each pocket.

An elongated channel 35, which is rectangular in transverse cross section and which extends parallel to the periphery of the raised member 25, is formed in the main body member 21 intermediate the two guide means. A first clamping bar 36 is adapted to seat in the channel with its upper surface flush with the supporting surface portions 21a, 23a. One or more pins 40 projecting upwardly from the channel bottom may cooperate with wells 41 in the clamping bar 36 to hold the bar in position in the channel. A second clamping bar 42 similar in size and shape to the bar 36 is adapted to seat atop the bar 36, and means on the bars are provided for clamping the bars together. This means may comprise studs 43 extending through openings in the bar 42 and cooperating with threaded openings in the bar 36.

Because of small variations in the diameter of the lead wires the plane surfaces of the clamping bars can not obtain a good grip upon each lead wire to hold each condenser properly in place. In order to correct this, I provide gripping means comprising an elongated member 44 of spring material riveted on the bar 42. As shown in FIGS. 2 and 4 the gripping member 44 is arcuate in transverse section and is narrower than the bar 42, whereby its side edges grip the wires between the bars when the bars are clamped together, thereby compensating for slight inequalities in the diameter of the lead wire.

In manufacturing condensers a plurality of disc-shaped condenser body members 50 may be positioned on the apparatus, one body member in each pocket 27. The body members 50 are of ceramic or other dielectric material and have conductive plates 51 on each side thereof. The condensers illustrated in FIG. 1 are single unit condensers, and the plates may comprise silver coatings which are circular and are centered on the dielectric discs, leaving a peripheral dielectric strip. In the two-unit condensers illustrated in FIG. 3, two plates may be provided on one side of each disc, these plates being designated at 51a and 51b, and the plates being separated by a center strip of the ceramic disc.

Lead wires 53 are placed with their ends engaging each respective plate. In the apparatus of FIG. 1 each lead wire may comprise an elongated loop having its ends crossed in "scissors" form, and in positioning condensers as shown, each condenser body member may be slipped between the crossed ends of the lead wires so that the lead wire ends engage the respective plates, and the condenser assembly may then be positioned on the apparatus with the condenser body member 50 received in the pocket 27 and with the lead wires positioned in the outside slots 33 of the guide means 32 and extending around the posts 30 which comprise the other guide means.

FIG. 3 shows a similar arrangement except that the lead wire loops 50 have their ends in engagement with the plates 51a and 51b on the same side of the ceramic disc, and another lead wire 54 may be formed as a U having its ends in engagement with the single plate 51 on the opposite side of two adjacent condenser body members.

After a condenser has been positioned in each of the pockets 27, the second clamping bar 42 may be placed atop the clamping bar 36 and the studs 43 may be tightened to clamp the two bars together with the lead wires therebetween and form a single readily portable assembly having the condenser body members 50 gripped between the lead wire ends. Any convenient number of condensers may be handled in such an assembly. For condenser discs having a diameter of $\frac{5}{16}$ inch, clamping bars having an over-all length of about 12 inches may be used to hold 21 condensers at a time; or 14 discs having a diameter of $\frac{1}{2}$ inch may be clamped between bars of similar length, if desired. Of course, the pockets 27 are formed on an arc of a circle having the same diameter as the discs to be positioned therein.

After the bars are secured together to clamp the wires and form the portable assembly, the assembly is removed

from the base portion and is positioned with the discs extending downwardly. With the assembly held in this position, the discs may be dipped in a fluxing agent. FIG. 5 shows the clamped assembly after it has been

5 moved out of the positioning apparatus. The assembly may then be inverted from the position of FIG. 5 and the discs may all be dipped simultaneously in a tank 60 (FIG. 7) having therein a fluxing agent 61. With the discs in the same position they may be dipped in molten solder 62 in another tank 63 which may be adjacent the flux tank 60 and which preferably has a cover 64 with an elongated narrow central opening 65 therein in order to prevent excessive fumes from escaping from the solder tank. The solder coats only the conductive plates and 10 the lead wire ends and does not stick to the edge portions of the ceramic discs, so the plates are not shorted. The assembly is again inverted while the solder in still liquid so that a globule of solder is formed in the junctures of the lead wires and the conductive plates 51 to strengthen 15 the solder connection. A plurality of assemblies may then be placed on a drying rack comprising spaced holder arms 66 mounted on a wall 67 having a hood 67a and having an opening connected by a pipe 68 to a source of suction in order to remove fumes from the hot solder. A 20 lip 67b may be provided so that flux droppings will fall back in the flux tank. Preferably the solder in the tank 63 is kept at a temperature of about 400° F. so that the solder remains liquid for a sufficient time for the operator to invert the assembly and place it on the drying rack.

25 When the solder has solidified a plurality of the clamped assemblies may be placed in a tray comprising peripheral angle irons 69 and legs 70, where the discs may be treated with trichloro ethylene vapor for degreasing the discs, and then may be dipped into polycyclopentadene which forms a 30 moisture-proof covering. After drying in a blast of hot or cold air, the discs may be dipped in a dielectric mixture, as for example, a thermosetting resin and mica mixture which forms a heavy dielectric sheath over the discs. If desired, at this stage the discs may be printed with color 35 code symbols, each disc being individually printed in conventional manner. The assembly is then placed in a paper cutter and the paper cutter blade is utilized to shear the lead wire loops, the shear line being designated at 40 71 in FIG. 5. After shearing, the studs 43 may be removed so that the condensers can be taken out of the 45 clamping bars and the manufacturing process is completed by handling the condensers individually. After removal from the clamping bars, groups of condensers may be 50 dumped in jars and baked to set the resin. After curing the resin the condensers may be placed in a basket and subjected to a strong vacuum for about a half hour to remove entrapped air. As a final step in the manufacture the condensers are coated with wax, preferably being 55 left in liquid microcrystalline wax at a temperature of 190-200° F. for about a half hour to impregnate the dielectric sheath with wax, and the condensers are then dumped and scattered so they will not stick together while they are cooled and dried.

While I have shown and described certain embodiments of my invention, it is to be understood that it is capable of many modifications. Changes, therefore, in the construction and arrangement may be made without departing from the spirit and scope of the invention as disclosed in the appended claims.

60 I claim:

1. Apparatus of the character described for making condensers, comprising: a base having a substantially horizontal supporting surface; an elongated raised portion on said surface having a plurality of pockets spaced in a line along the periphery thereof, each adapted to receive a condenser body member; guide means opposite each pocket for positioning lead wires in contact with but unattached to the opposite sides of each condenser body member; means providing a channel generally parallel to said raised portion intermediate at least a portion of said

guide means and said pockets, said wires extending across said channel; a first clamping bar adapted to seat in said channel beneath said wires with its upper surface substantially flush with said supporting surface; a second clamping bar adapted to cooperate with said first bar to clamp said wires and form a single readily portable assembly having said body members gripped between the lead wire ends; and gripping means comprising an elongated member of spring material mounted on one of said bars, said gripping means being arcuate in transverse section whereby its side edges grip said wires between said bars.

2. Apparatus of the character described for making condensers, comprising: an elongated base having a substantially horizontal supporting surface; a raised portion extending longitudinally of said surface having a plurality of generally semi-circular pockets spaced in a straight line along the periphery thereof, each adapted to receive a portion of a disc-shaped condenser body member; guide means projecting above the plane of said surface providing means opposite each pocket for positioning lead wires in contact with but unattached to the opposite sides of each condenser body member; means providing an elongated channel rectangular in cross section and extending parallel to the periphery of said raised portion intermediate at least a portion of said guide means and said pockets, said wires extending across said channel, a first clamping bar adapted to seat in said channel beneath said wires with its upper surface flush with said supporting surface; a second clamping bar adapted to seat atop said first bar and wires; and means on said bars for clamping said bars together to clamp said wires and form a single readily portable assembly having said body members gripped between the lead wire ends.

3. Apparatus of the character described for making condensers, comprising: an elongated base having a substantially horizontal supporting surface; a raised portion extending longitudinally of said surface having a plurality of generally semi-circular pockets spaced in a straight line along the periphery thereof, each adapted to receive a portion of a disc-shaped condenser body member; first guide means opposite each pocket; second guide means opposite each pocket intermediate said first guide means and said pockets, said first and second guide means providing a plurality of vertical guides for positioning lead wires in contact with but unattached to opposite sides of each condenser body; means providing an elongated channel rectangular in cross section and extending parallel to said raised portion intermediate said first and second guide means, said wires extending across said channel, a first clamping bar adapted to seat in said channel beneath said wires with its upper surface flush with said supporting surface; a second clamping bar adapted to seat atop said first bar and wires; gripping means comprising an elongated member of spring material mounted on said second bar, said gripping means being narrower than said bars and being arcuate in transverse section whereby its side edges engage said wires between said bars; and means on said bars for clamping said bars together to clamp said wires and form a single readily portable assembly having said body members gripped between the lead wire ends.

4. Apparatus of the character described for making condensers, comprising: a base having a supporting surface; a raised portion on said surface having a plurality of pockets spaced in a line along the periphery thereof, 65

each adapted to receive a condenser body member; a post projecting from said supporting surface opposite each pocket, each post having a vertical slot therein; second guide means opposite each pocket intermediate said first 5 guide means and said pockets, said first and second guide means providing a plurality of vertical guides for positioning lead wires in contact with but unattached to opposite sides of each condenser body; means providing a channel generally parallel to the periphery of said raised portion intermediate said first and second guide means; and a clamping device adapted to seat in said channel to clamp said wires and form a single readily portable assembly having said body members gripped between the lead wire ends.

5. Apparatus for assembling condenser components, comprising: a base having a substantially horizontal supporting surface; an elongated raised portion on said surface having a plurality of pockets spaced in a line along the periphery thereof, each adapted to receive a condenser body member; guide means opposite each pocket for positioning lead wires having their ends in opposed contact with but unattached to the opposite sides of each condenser body member; means providing a channel generally parallel to said raised portion intermediate at least 20 a portion of said guide means and said pockets, said wires extending across said channel; a first clamping bar removably seated in said channel beneath said wires with its upper surface substantially flush with said supporting surface; a second clamping bar cooperating with said first 25 bar to clamp said wires and force their ends into gripping contact with said condenser bodies and form a single readily portable assembly having said body members gripped between the lead wire ends; said bars including gripping means to augment the grip on said wires, and 30 35 means to force and hold said bars together.

6. Apparatus for assembling condenser components, comprising: an elongated base having a substantially horizontal supporting surface; a raised portion extending longitudinally of said surface having a plurality of pockets spaced in a straight line along the periphery thereof, each 40 adapted to receive a portion of a condenser body member; guide means projecting above the plane of said surface providing means opposite each pocket for positioning lead wires having their ends in opposed contact with but unattached to the opposite sides of each condenser body member; means providing an elongated channel extending parallel to the periphery of said raised portion intermediate at least a portion of said guide means and said pockets, said wires extending across said channel, a 45 first clamping bar removably seated in said channel beneath said wires with its upper surface flush with said supporting surface; a second clamping bar adapted to seat atop said first bar and wires and force their ends into gripping contact with said condenser bodies; and means on said bars for clamping said bars together to clamp said 50 55 wires and form a single readily portable assembly having said body members gripped between the lead wire ends.
